UNITED STATES PATENT OFFICE

CARL H. ZWERMANN, OF ROBINSON, ILLINOIS

DESIGN FOR A LAVATORY

Application filed September 8, 1930. Serial No. 36,902. Term of patent 14 years.

To all whom it may concern:

Be it known that I, CARL H. ZWERMANN, a citizen of the United States, residing at Robinson, in the county of Crawford, State of Illinois, have invented a new, original, and ornamental Design for a Lavatory, of which the following is a specification, reference being had to the accompanying drawing, forming part thereof.

The figure is a perspective view of my new design, the body portion of the design being symmetrical in cross section.

I claim:

The ornamental design for a lavatory as shown and described.

CARL H. ZWERMANN.
